UNDER-CUTTING TOOL

Filed March 21, 1947

UNITED STATES PATENT OFFICE

2,537,709

UNDER-CUTTING TOOL

Freeman Schermerhorn, Pierz, Minn., assignor of
one-half to William Holroyd, Foley, Minn.

Application March 21, 1947, Serial No. 736,326

1 Claim. (Cl. 29—96)

1

This invention relates to improvements in lathe tools, and more particularly to an improved undercutting attachment for lathes, especially although not necessarily for undercutting laminations and the like of a cylindrical member, such as the mica laminations of an electric motor commutator.

A primary object of this invention is to provide a simple and efficient tool of the character indicated whose cutting element is readily replaceable.

Another important object of this invention is to provide a tool of the character indicated which is composed of a minimum number of simple and rugged parts which are easily made and assembled at low cost, and which can be made from scrap material so as to further reduce the cost.

Other important objects and advantageous features of this invention will be apparent from the following description and the drawings appended thereto, wherein merely for purposes of illustration, a preferred embodiment is set forth in detail.

In the drawings:

Figure 1 is a top plan view thereof;

Figure 2 is a bottom plan view;

Figure 3 is a left hand side elevation;

Figure 4 is a right hand side elevation;

Figure 5 is a transverse section taken through 5—5, Figure 1, on a somewhat enlarged scale;

Figure 6 is a fragmentary longitudinal sectional view on an enlarged scale, taken on the line 6—6 of Figure 3, and

Figure 7 is a side elevation, on a somewhat enlarged scale, of the blade retaining plate, partly broken away to show structural details.

Referring in detail to the drawing, the herein illustrated tool comprises a shank 8, for mounting on a lathe tool-post (not shown), of relatively narrow, flat, parallel sided form terminating at its heel in a downwardly angulated surface 9 and flared at its opposite end, as indicated at 10, into a generally rectangular head 11.

As shown in Figures 3 and 4, the upper surfaces of the shank 8 and flared portion 10 are forwardly and downwardly curved, as indicated at 12, and the lower surfaces thereof are forwardly and upwardly curved, as indicated at 13, with the result that the forward end of the head 11, which is rounded as indicated at 14, is of substantially smaller vertical dimension than the shank 8.

The top of the head 11 is milled to provide thereacross a horizontal blade retaining plate slot 15, and forwardly therefrom with a blade seating slot 16 on an appropriately lower level. The right hand side of the head 11 is formed with

2

a vertical slot 17 to accommodate a portion of the retainer plate. A vertical screw threaded hole 18 is formed through the head 11 midway between the sides of the head and an appropriate distance 5 behind the front edge of the slot 15, to accommodate a clamping stud 19.

The blade 20, which may appropriately be a length of discarded hacksaw blade, with the slanting sides of the teeth 21 toward the right hand 10 side of the head 11, seats in the blade slot 16 with its toothed edge extending beyond the terminal 14 of the head, and is held in place by the blade retainer plate 22.

The retainer plate 22 comprises a flat rectangular horizontal plate portion 23, fitting the dimensions of the slot 15 and having a downturned forward edge 24 shaped to conformably engage the upper surface of the blade 20, and a plate-like vertical side 25 to engage in the slot 17 20 of the head 11.

The horizontal plate portion 23 is formed with a smooth hole 26 freely but closely passing the threaded shank of the clamping stud 19, this hole being so positioned that when the stud is passed 25 therethrough and threaded into threaded hole 18 of the head 11, the blade retainer plate portion 23 will conform to the head slot 15 and its vertical flange 25 will conformably engage the side slot 17. With the blade 20 in place in the slot 16, further tightening of the stud 19 operates to forcibly 30 engage the downturned edge 24 with the blade 20 so as to securely retain the same in place with its back edge against the back of the blade slot 16 and its right hand end against the flange 25. In this way the blade 20 cannot shift or get out of 35 alignment in the tool in ordinary use, but can be quickly and easily removed and replaced by loosening and retightening the stud 19.

Various modifications and changes are contemplated and may obviously be resorted to without departing from the spirit and scope of the invention as claimed hereinafter.

Having described the invention, what is claimed as new is:

An under-cutting tool for mounting in a tool post of a lathe, comprising an elongated shank having a forward end provided with a widened head, said head having a top surface provided with a stepped portion including an outer lower 50 step and an inner upper step, said lower step opening outwardly of the forward end of the head and each of the steps extending from side to side of the head, said head having a threaded bore opening upwardly into the inner upper step, a 55 blade retaining plate conformably seating in said

inner upper step having a forward downturned edge extending toward the lower step, a transversely elongated blade conformably seated in said lower step beneath the downturned edge of the blade retainer plate having a transversely extending cutting edge spaced outwardly from the forward end of said head, said blade having a back edge abutting against a portion of the head disposed between the steps, said head having a threaded bore opening upwardly into the inner upper step, and a clamping stud extending downwardly through the blade retainer plate and threadedly engaging in said threaded bore for clamping the plate against the upper step and for retaining the downturned forward edge of the plate in clamping engagement with the blade for clamping said blade against the outer lower step, said blade retaining plate having a depend-

10
5

ing flange at one side edge thereof engaging a side edge of the head and one end of the blade for accurately positioning and retaining the blade against shifting movement transversely of the head, said cutting edge of the blade comprising a row of teeth all inclined in a direction away from the depending flange of the blade retainer plate.
